PATENTED JULY 17, 1906.

J. B. HAMMOND.
PRINTING MECHANISM FOR TYPE WRITERS.
APPLICATION FILED MAR. 24, 1905.

APPLICATION FILED MAR. 24, 1905.

Fig. 3.

Fig. 1.

A detailed technical line drawing of a mechanical assembly. At the top, a small rectangular component with a central hole is shown, labeled with the number '6' and a small 'd' below it. Below this is a larger circular gear-like component with a central hub. The hub contains several numbered parts: '15' on the left, '16' at the top, '17' on the left side of the hub, '18' on the left side of the hub, '19' on the right side of the hub, '20' at the bottom, '23' on the left side of the hub, '24' on the right side of the hub, '25' on the right side of the hub, '26' on the right side of the hub, and '27' on the right side of the hub. A lever mechanism is attached to the right side of the hub, featuring a curved arm labeled '28' and a slot labeled '25'. The entire assembly is mounted on a vertical shaft.

UNITED STATES PATENT OFFICE.

JAMES B. HAMMOND, OF NEW YORK, N. Y.

PRINTING MECHANISM FOR TYPE-WRITERS.

No. 825,966.

Specification of Letters Patent.

Patented July 17, 1906.

Application filed March 24, 1905. Serial No. 251,835.

To all whom it may concern:

Be it known that I, JAMES B. HAMMOND, a citizen of the United States, residing at Sixty-ninth street and East River, New York, N. Y., have invented certain new and useful Improvements in Printing Mechanism for Type-Writers, of which the following is a specification.

My invention relates to type-writers of the class in which the characters are carried by a wheel or similar rotary element, and it consists in the features and combination and arrangement of parts hereinafter described, and particularly pointed out in the claims.

15 In the accompanying drawings, Figure 1 is a plan view of the printing elements of a type-writer embodying my invention. Fig. 2 is a central vertical sectional view of Fig. 1. Fig. 3 is a view of a detail.

20 My invention concerns more particularly the means for retaining in place the rotary shuttle or wheel carrying the characters. This rotary shuttle is in the form of a continuous ring 1, having a flange 2 at its upper edge extending continuously around the same, the said flange resting upon the upper edge of an anvil 3, which is suitably held upon a center-post 4. Antifriction bearings or balls may be interposed, as at 5, between 25 the flange of the shuttle and the upper edge of the anvil. The shuttle coöperates with a hammer, (indicated at 6,) which, as in the ordinary Hammond type-writer, is provided with a plurality of faces, any one of which 30 may be brought into coöperative relation with the shuttle.

In order to hold the shuttle in place on the anvil, I provide retainer 7 consisting of bars 7, supported on the upper edge of the cross-arms 8 of the anvil, to which the said bars are held by screws 9, passing down through slots 10 in the said bar. The bars have cross-arms at their ends, as shown at 11; and these arms are in turn provided with fingers 12, arranged in divergent relation and reaching over the inner edges of the continuous flange of the shuttle. At their inner ends the arms or bars 7 are turned upwardly and thence curved outwardly, as at 13, whereby they 45 may be manipulated. In order to remove the shuttle, it is simply necessary to grasp the ends 13 of the bars 7 and press them inwardly toward each other, thus withdrawing the overlying fingers 12 from the shuttle-flange, and then the entire shuttle may be 50 lifted from the machine. This effect is also

rendered possible because the shuttle-arm 14 common in this class of machines has its upturned end 15 engaging in a notch 16 in the inwardly-extending flange, this construction 60 offering no resistance to the free removal of the shuttle. In order to place the shuttle in position and retain it, it is simply necessary to drop it down upon the anvil, so that its continuous flange will rest upon the upper 65 edge thereof or upon the ball-bearings carried thereby, and then by pressing the finger down between the outwardly-curved ends 13 of the bars 7 the said bars will be pressed apart, and the fingers 12 will be thrust over 70 the flange of the shuttle, and thus the shuttle will be retained against vertical displacement.

In order to hold the anvil on the center-post against vertical displacement, I provide 75 a vertical-extending rod 17, extending up from a part of the machine and having an inwardly-extending arm 18, engaging a groove or kerf in the side of the anvil-arm, as at 19 in Fig. 2. This inwardly-extending arm 18 80 is provided with a bent end 20, Fig. 1, and when the anvil is to be removed this arm can be swung aside in the direction of the arrow, Fig. 1, to thus remove it from the kerf 19, whereupon the anvil may be removed vertically. The shuttle being of continuous ring 85 form carries a plurality of sets of characters, and I have indicated these at a, b, and c. Those at a are adapted for use in writing Braille and consist of projections having pits 90 formed therein adapted to coöperate with points carried by the hammer in a vertical row and one of which is shown at d, Figs. 1 and 3. This arrangement for printing Braille I have improved by forming a shoulder on 95 the hammer at e, surrounding the point and adapted to coöperate with the edge of the pit and limit the entrance of the point into the pit, so that the paper will be embossed without being punctured. The relation of the 100 parts is such that the shoulder e will properly limit the entrance of the point into the pit, and thus prevent puncturing of the paper.

I claim as my invention—

1. In a type-writer, the combination of an 105 anvil of ring shape, a ring-shaped shuttle having a flange at its extreme upper edge overlying the upper edge of the anvil, a shuttle-arm within the anvil engaging said flange to operate the shuttle, and a retainer reaching over the flange of the shuttle and adjustable to and from said position to permit 110

the removal and replacing of the shuttle by a vertical movement, substantially as described.

2. In a type-writer, the combination of an anvil of ring shape, a ring-shaped shuttle having a flange at its extreme upper edge overlying the upper edge of the anvil, a shuttle-arm within the anvil engaging said flange to operate the shuttle, and a retainer reaching over the flange of the shuttle and adjustable radially to and from said position to permit the removal and replacing of the shuttle by a vertical movement, substantially as described.

15 3. In a type-writer, the combination of an anvil of ring shape, a ring-shaped shuttle, a shuttle-arm within the anvil-engaging part of the shuttle to operate the same and a retainer reaching over the upper edge of the anvil and over the upper part of the shuttle and adjustable to and from the said position to permit removal and replacing of the shut-

tle by a vertical movement, substantially as described.

4. In combination, an anvil, a ring-shaped shuttle and a pair of retainers movable radially outward to overlie the shuttle to hold the same in place and movable radially inward to permit the removal of said shuttle vertically, substantially as described. 25

5. In combination, an anvil, a ring-shaped shuttle and a pair of retainers movable radially outward to overlie the shuttle to hold the same in place and movable radially inward to permit the removal of said shuttle vertically, said retainers having finger-pieces at their inner ends extending upwardly, substantially as described. 30 35

In testimony whereof I affix my signature in presence of two witnesses.

JAMES B. HAMMOND.
